UNITED STATES PATENT OFFICE.

FREDERICK W. FELSBERG, OF DAYTON, KENTUCKY, ASSIGNOR TO THE TRIUMPH ICE MACHINE COMPANY, OF CINCINNATI, OHIO.

VALVE FOR ICE-MACHINES.

No. 826,555.

Specification of Letters Patent.

Patented July 24, 1906.

Application filed June 14, 1905. Serial No. 265,150.

To all whom it may concern:

Be it known that I, FREDERICK W. FELSBERG, a citizen of the United States, residing at Dayton, in the county of Campbell and State of Kentucky, have invented certain new and useful Improvements in Valves for Ice-Machines, of which the following is a full, clear, and exact specification.

My present invention relates to improvements in the construction of valves particularly adapted for use in ice-making machinery.

It often happens that in certain parts of refrigerating or ice-making machines in which controlling-valves are employed the space available for the longitudinal movement of the valve-spindle is so small that it is impossible to employ the ordinary construction of valve having considerable longitudinal movement of the spindle; and it is one of the objects of my present invention to produce a valve that will operate efficiently and easily under conditions which will not permit the use of the ordinary form of valve.

A further object of my invention is to do away with the rotary movement of the valve on its seat and the consequent rapid wearing away of the valve and seat, which necessitates frequent renewals. Frequent renewals are a source of considerable inconvenience and expense, particularly in large valves of ice-machines of considerable capacity.

A further object of my invention is to produce a valve so constructed and arranged that the stuffing-box surrounding the valve-spindle may be repacked while the valve is under pressure without permitting the ammonia or other gas controlled by said valve to escape.

The invention therefore consists of a globe-valve in which the valve-disk is arranged to move up or down on the valve-spindle as the latter rotates, said spindle maintaining a positive position relative to the valve-casing. The valve-disk is preferably constrained to move rectilinearly and without rotation.

The invention further consists of a double-seated valve-disk mounted for rectilinear movement without rotation on a rotatable valve-spindle, a stuffing-box for said spindle, a valve-seat with which said valve-disk engages when at one limit of its movement, and a second valve-seat with which said disk en-

gages when at the opposite limit of its movement, said disk when in its latter position sealing the opening through which the valve-spindle passes, so as to permit the valve-stuffing-box to be repacked while the pressure is maintained in the valve-casing.

In the accompanying drawings, which illustrate the preferred embodiment of my invention, Figure 1 is an end elevation of my improved valve. Fig. 2 is a sectional elevation on the line 2 2 of Fig. 1, the valve being shown closed on its lower seat; and Fig. 3 is a sectional elevation similar to Fig. 2 of part of the valve, showing same closed on its upper seat.

Referring now to the drawings, the valve casing or body 5 is provided with the bridge 6, carrying the lower seat 7, upon which the valve-disk 8 is adapted to rest when the valve is in its closed position, as shown in Fig. 1. This valve-disk is provided with a cylindrical extension 8^a, threaded on its inner surface and engaging the threaded portion 13 of the valve-spindle 12, so as to have an up-and-down movement on said spindle as the latter is rotated by the handle 20. The valve-disk 8 is constrained to move rectilinearly without rotation by means of the dowel-pins 24, mounted in the guide-sleeve 11 and engaging the grooves 25, formed in the cylindrical extensions 8^a. The top of the valve-disk 8 is provided with a valve-seat 9, which is adapted to engage the upper valve-seat 23 when the valve-disk is in its upper limiting position. (Shown in Fig. 3.) The valve-seats 10 and 23 are of Babbitt metal in dovetail grooves. The valve-spindle 12 is prevented from moving longitudinally by the collar 14, which is held between the shoulders 15^a, formed on the valve-hood 15 and the upper surface of the guide-sleeve 11. The guide-sleeve has formed thereon an annular collar 27, which rests upon the annular shoulder 28 in the valve-casing. Said sleeve is held tightly in position by the hood 15 when the latter is fastened in position on the casing by the nuts 16 and is prevented from rotating by means of the pin 21. Located at the joint between the casing 5, the hood 15, and the sleeve 11 is a suitable packing 22, which prevents leaking of the ammonia at this point. The upper part of the valve-spindle is surrounded by a stuffing-box comprising the

2
packing 19, the thimble 18, and the cap-nut 17, screwed on the hood 15. A vent 26 is provided to prevent the pocketing of fluid in chamber 29. When the valve is in the position shown in Fig. 3, it is readily seen that the passage-way through the valve-hood 15 and sleeve 11 occupied by spindle 12 is effectually sealed, so that the nut 17 and thimble 18 may be removed and the stuffing-box 10 repacked while pressure is maintained in the valve-casing.

15 The various parts of the valve are readily accessible and can be reached by simply removing nuts 16. Rotary movement of the valve-spindle without longitudinal movement causes a reduction of the wear and tear on the packing in the stuffing-box, and the rectilinear movement of the valve-disk without rotary movement prevents grinding on 20 the valve-seats and gives the valve longer life and renders it more efficient and effective in its operation.

25 In the appended claims I aim to cover all changes and modifications of my invention which do not involve a departure from its spirit and scope.

Having thus described my invention, what I claim as new, and desire to secure by Letters Patent, is—

30 A valve, comprising a casing, provided with a hood, a valve-disk, a spindle, means for rotating said spindle, means for preventing a longitudinal movement thereof, means for causing said disk to move up or down on said spindle as the latter rotates, said means 35 consisting of an internally-threaded cylindrical extension on said disk surrounding and engaging a threaded end of said spindle, and a guide-sleeve surrounding said cylindrical extension and provided with means for constraining said disk to move rectilinearly without rotation, said guide-sleeve being separate from the valve-casing and hood and held in position between said casing and hood and provided with means for preventing its rota- 40 45 tion.

In testimony whereof I affix my signature in the presence of two witnesses.

FREDERICK W. FELSBERG.
